(57) **CLAIM**

The ornamental design for a sole for golf shoe, as shown and described.

DESCRIPTION

FIG. 1 is a perspective view of a sole for golf shoe.

FIG. 2 is a top plan view of the sole of FIG. 1.

FIG. 3 is a bottom plan view of the sole of FIG. 1.

FIG. 4 is a left side view of the sole of FIG. 1.

FIG. 5 is a right side view of the sole of FIG. 1.

FIG. 6 is a front end view of the sole of FIG. 1; and,

FIG. 7 is a back end view of the sole of FIG. 1.

The dashed lines showing the various parts of the sole are for illustrative purposes only and form no part of the claimed design.
